UNITED STATES PATENT OFFICE.

ALFRED SMALLWOOD, OF LONDON, ENGLAND.

CONVEYING APPARATUS.

Application filed March 8, 1920. Serial No. 364,268.

To all whom it may concern:

Be it known that I, ALFRED SMALLWOOD, a subject of the Kingdom of Great Britain, residing at 42 Hargrave Park, Highgate, 5 London, N., in the county of Middlesex, England, have invented Conveying Apparatus, of which the following is a specification.

This invention comprises a device or apparatus for conveying or transporting goods, particularly as a device for charging furnaces.

According to the present invention, I provide a device in the nature of a barrow or trolley having two wheels, a supporting part or fork projecting forwardly therefrom, and a handle or operating part extending rearwardly therefrom. The forwardly extending part or fork is adapted 20 to be located underneath the goods, such as a receptacle containing malleable castings, and by depressing the rear or operating part the goods can be elevated, conveyed, and advanced into the working chamber of 25 the furnace. In order to enable the goods to be readily elevated and balanced during the conveying and charging apparatus, I combine with the apparatus an adjustable weight adapted to be displaced rearwardly 30 to balance the goods. This weight is adapted to be actuated from a distance, i. e. from the rear of the operating mechanism.

In order that this invention may be clearly understood and readily carried into practice, reference may be had to the appended explanatory sheet of drawings, upon which:—

Figure 1 is an elevation of a charging device incorporating an embodiment of the 40 present invention.

Figure 2 is a plan of the charging device shown in Figure 1.

Figure 3 illustrates a detail of the mechanism incorporated in the charging device 45 shown in Figures 1 and 2.

In a convenient embodiment of the present invention, the frame comprises a forwardly extending fork *a* which is rigid with a rearwardly extending horizontal frame in the 50 nature of parallel rails *b* which at their rear extremity are extended in unitary formation to a suitable handle *c*. Upon these rails a weight *d* fitted with rollers or wheels *e* is adapted to run forwardly and 55 rearwardly. In the vicinity of the charger wheels *f* which are located at or near the

juncture of the fork or carrier portion with the rails, a chain pulley *g* is provided; another chain pulley *h* is provided around which and the pulley *g* a chain extends and 60 is coupled to the running weight *d*, so that by rotation of the rear pulley the weight can be advanced towards or displaced away from the running wheels *f* of the charger. Co-axially with the chain wheel *h* and fixed 65 to rotate therewith is a chain pulley *i*. From this a chain *j* extends to a chain pulley *k* located in the region of the handle *c*. *l* is a spur wheel fixed to rotate co-axially with the pulley *k*, the said spur wheel *l* being in mesh with a spur wheel *m* in the countershaft *n* (Figure 3). The said countershaft *n* is mounted in a supporting bracket *o* and is adapted to be rotated, as for instance by a handle *p*.

A clutch, preferably of the friction type, is provided in combination with the chain gear appertaining to the weight, being advantageously provided in combination with the countershaft *n* and being adapted to 80 provide for the retention of the weight in any position in which it may be located. In the construction shown, *q* is a sleeve appropriately anchored from rotation to the bracket *o*, the said sleeve *q* having a taper 85 extension which is split so that it may be contracted to grip the shaft *n*. This contraction may be effected by a nut *r* screwed upon the sleeve *q* and also having a female taper formation adapted to co-operate with the taper formation upon the sleeve. By rotating the nut *r* in an appropriate direction, as for instance by a suitable lever arm, the extension of the sleeve *q* is contracted to 90 grip the shaft *n*, and thereby lock the chain gear and balance weight *d* from movement.

The apparatus may be moved with or without the load by the handle *c*, but additional gear may be provided for propelling the apparatus. With this object in view, the axle of the wheels *f* may be encircled by a worm wheel *s* adapted to be clutched to said axle; the said worm wheel *s* is in mesh with a worm *t* provided upon a shaft *u* coupled by an universal joint *v* with another shaft *w* having a detachable handle *x*, which latter may be operated from the rear of the apparatus to rotate the axle in relation to which the wheels *f* are fixed. For clutching the worm wheel *s* to the axle of the wheels *f*, a dog clutch *z* is provided adapted to be operated by a clutch operating fork 105

2 which is mounted upon and oscillated by a shaft 3 fitted with a lever arm 4.

In charging, the fork is introduced below the goods which are suitably supported 5 above the ground surface, the charging fork being located at a lower level for this purpose, after which the weight is actuated to recede until the load can be readily conveyed and introduced into the furnace. The weight 10 is then displaced towards the load, when the latter can readily be deposited, and the charging apparatus withdrawn.

What I claim as my invention and desire to secure by Letters Patent is:—

- 15 1. A load conveying apparatus comprising coaxial running wheels for supporting the apparatus on the ground, an operating structure supported by said wheels, the operating structure including a forwardly projecting portion terminating in a load carrying fork, and a rearwardly projecting portion terminating in a handle adapted for use by the operator of the apparatus, a counter-weight movable on the rearward projection 20 of the operating structure and means adjacent the handle for positively rotating the supporting wheels to advance the apparatus over the ground.
- 25 2. A load conveying apparatus, including coaxial supporting wheels for supporting the apparatus on the ground, an operating structure carried by said wheels, the oper-

ating structure comprising a fork projecting forward of the wheels and a portion projecting rearward therefrom and connected at 35 its rear end with a handle, an adjustable weight on the operating structure, means adjacent the handle for imparting movement to said counterweight on the operating structure, means operable from the rear end of the operating structure for imparting rotary movement to said wheels, and a clutch interposed between the last mentioned means and the wheels.

3. In a load conveying apparatus, the combination of coaxial supporting wheels for supporting the apparatus on the ground an operating structure carried by said wheels, the operating structure comprising a fork projecting forward of the wheels and a portion projecting rearward therefrom and connected at its rear end with a handle, an adjustable weight on the operating structure, means adjacent the handle for imparting movement to said counterweight on the operating structure, means operable from the rear end of the operating structure for imparting rotary movement to said wheels, a clutch interposed between the last mentioned means and the wheels and means adjacent 40 the handle for actuating the clutch.

In witness whereof I have hereunto set my hand.

ALFRED SMALLWOOD.
